Patented Dec. 31, 1918.

UNITED STATES PATENT OFFICE.

GEORGE B. WILLCOX, OF SAGINAW, MICHIGAN.

SPOUT.

1,289,587.

Specification of Letters Patent. Patented Dec. 31, 1918.

Application filed March 11, 1916. Serial No. 83,586.

To all whom it may concern:

Be it known that I, GEORGE B. WILLCOX, a citizen of the United States, residing at Saginaw, in the county of Saginaw and State of Michigan, have invented certain new and useful Improvements in Spouts; and I do hereby declare the following to be a full, clear, and exact description of the invention, such as will enable others skilled in the art to which it appertains to make and use the same.

This invention is a pouring spout for use on containers such as salt cartons and the like, and the improvement relates more particularly to certain novel features of construction in spouts of the class adapted to project from the container when in use and to serve as a cover or closure for the spout opening when not in use.

The improvement relates more specifically to an improved means for yieldingly holding the spout in its open position.

A spout to which my improvement is applied is shown in the accompanying drawings, in which Figure 1 is a perspective view of the end wall of a carton with the spout in position for pouring.

Fig. 2 is an enlarged transverse section on the line 2—2 of Fig. 1.

Fig. 3 is a front diagrammatic view of the spout opening.

As usually constructed, the spout consists of a bottom member 1 and quadrant-shaped sides 2. The bottom member is hinged to the wall of the carton at the lower edge 3 of the spout opening in any suitable manner, and the sides 2 are provided inside the carton with suitable projections or stops 4 adapted to engage the wall of the carton to prevent the spout from being accidentally drawn out of the carton.

My present invention relates to an improved means for yieldingly retaining the spout in its open or outwardly projected position and for maintaining the correct shape and parallel arrangement of the sides 2, 2.

To yieldingly hold the spout in its opened position, I so shape the sides 2, 2, or one of

them, that the part of the outer edge nearest the stop 4 will press into and bind against the wall of the carton at the upper edge 5 of the spout opening 6 when the spout is in its opened position.

Slits 7 may be formed in the wall of the carton to receive and guide the sides 2 if desired, the depth of the slits being such that the part of the sides 2 nearest the free end of the spout will not bear against the ends of the slits when the spout is closed or only slightly opened, but when the spout is opened to the position for pouring, the wider or outwardly projecting parts 8 of the sides will engage the carton wall at the extremities of the slits with sufficient grip to yieldingly hold the spout in its open position. The sides 2 are preferably parallel with each other and with the edges of the spout opening. The radially extended parts 8 of the sides 2 may be of any shape adapted to engage the ends of the slits; or to engage the upper edges of the opening in the carton if the slits are not used, as the case may be, but I preferably make the sides 2, 2 of quadrant shape and slightly eccentric, the radius at 8 being greater than at other parts of the quadrant, so that the spout will open freely, but the peripheries of its sides, as at 8, will yieldingly bind against the edge of the carton wall when the spout is in its opened position.

By the means above described, I have produced a spout which will remain opened and is not likely to become loose or to close accidentally, and will retain its shape and neat appearance.

As an article of manufacture the spout can be produced in large quantities at very small expense.

Having thus described my invention, what I claim and desire to secure by Letters Patent is:

1. In a container having a wall formed with a spout opening, a spout hinged in said opening, a side on said spout, one edge of said side being slightly eccentric to the hinge to form a wedge-member adapted to frictionally engage the edge of said con-

tainer wall at the upper edge of said opening and thereby hold the spout in its open position.

2. A container having a wall formed with
5 a spout-opening and slits extending therefrom, a spout hinged in said opening, a side on said spout, one edge of said side being slightly eccentric to the hinge to form a wedge-member adapted to frictionally en-

gage the edge of said container wall at the 10 upper end of said slit and thereby hold the spout in its open position.

In testimony whereof, I affix my signature in presence of two witnesses.

GEORGE B. WILLCOX.

Witnesses:

JOSEPH V. CARPENTER,
NELLIE M. ANGUS.
